UNITED STATES PATENT OFFICE.

EDWARD F. DRAKE, OF MILLER'S FALLS, MASSACHUSETTS.

CUSPIDOR OR CUSPIDOR-HOLDER.

SPECIFICATION forming part of Letters Patent No. 425,497, dated April 15, 1890.

Application filed June 22, 1889. Serial No. 315,159. (No model.)

To all whom it may concern:

Be it known that I, EDWARD F. DRAKE, of Miller's Falls, county of Franklin, State of Massachusetts, have invented an Improvement in Cuspidors or Cuspidor-Holders, of which the following description, in connection with the accompanying drawings, is a specification, like letters on the drawings representing like parts.

This invention has for its object to improve cuspidors or cuspidor-holders of the kind commonly termed "Ottoman" cuspidors. In the use of cuspidors of this kind I have found it very desirable to have the cover of the holder detachable or removable bodily at will, so that the body of the holder may be cleaned without danger of damaging the cover. I have also found it desirable to have the cover thrown back automatically when released, instead of requiring it to be thrown back by the foot.

This invention consists in a cuspidor-holder provided with a hinged cover removable bodily at will when lifted; also in the combination, with a cuspidor-holder having a cover, of means for automatically throwing the cover back or open.

Figure 1 is a side elevation and partial section of a cuspidor-holder embodying this invention, and Figs. 2, 3, and 4 details to be referred to.

The body *a* of the cuspidor-holder, preferably of metal, having a flanged base *a'*, is herein shown as adapted to receive within it a cuspidor of any usual construction, or it may itself, if desired, be used as a cuspidor. A plate *b* is riveted or otherwise secured to the wall of the said body, as shown, said plate forming one leaf of a hinge, the other leaf *b'* of which is secured to the cover *c*. The pintle *b²* of the hinge is attached to the leaf *b'* by the posts *b³*, (see Fig. 2,) having portions at either end to be engaged by the hooked ears *b⁴* of the leaf *b*. It will be seen that the ears *b⁴* are not turned completely over, but leave a space at the under side to permit the pintle *b²* of the hinge to be withdrawn, if desired, when the cover is in a vertical position. The pintle *b²* of the hinge is retained in its place under the ears *b⁴* by the action of the spring *s*, said spring being formed, as herein shown,

of a wire bent back upon itself at *s'*, (see Fig. 2,) and slipped under the hook or eye *a³*, formed upon the wall of the body *a*. The two arms *s* of the wire encircle the pintle *b²* 55 between the posts *b³*, and thereafter the wire is extended beneath and made to bear against the under side of the cover *c*.

The tendency of the spring, shaped as described, is to throw the cover back into its 60 dotted-line position, Fig. 1.

At a point diametrically opposite to the hinge the cover is provided with a hook or eye *c'*, which is engaged by the hooked end *f'* of a flat spring or latch *f*, secured to the wall 65 of the body *a*, the said latch holding the cover in its lowermost or closed position.

The spring or latch *f* shown is offset at a point below the hook *f'*, (see Fig. 1,) and has formed upon its inner face an inclined projection or cam *f²* to be acted upon by a releasing device *H*, consisting of a wire, as shown, which is bent to embrace the catch, a portion of the same extending down through the flange *a'*, after which the shank of the 75 said hook or latch is turned upward through the said flange and is surrounded by a spring *h'* and provided with a foot-piece *h*. The spring *h'* acts to keep the foot-piece *h* and loop *h⁴* normally in an elevated position, as 80 shown in the drawings.

It will be seen that by depressing the foot-piece *h* the loop part of the releasing device will be drawn down, and, acting upon the inclined face of the projection *f²*, will throw the 85 upper free end of the spring or latch *f* outward, disengaging the hook *f'* from the hook or eye *c'* and allowing the spring *s* to throw back the cover, as shown in dotted lines, Fig.

1. Upon allowing the foot-piece to return to 90 its normal or elevated position the spring *f* will also return to its normal position to be engaged by the hook or eye *c'* when the cover *c* is closed.

The construction of the hinge is such that 95 when the cover in its elevated position is depressed the said spring will slide through the hook or eye *a³* far enough to permit the pintle *b²* to be disengaged from the ears *b⁴*, when the cover may be readily lifted off.

In replacing the cover the spring *s* will first be inserted in the hook or eye *a³*, when the

pintle may readily be passed down and under the ears b^x .

The cover is shown detached in Fig. 4.

I do not desire to limit myself to the precise construction shown, as the same may be varied considerably and still come within the scope of this invention.

I claim—

1. The body a of a cuspidor or cuspidor-holder, provided with a hinged cover removable bodily at will when lifted, and mechanism whereby the cover may be thrown open, substantially as described.

2. The body a of a cuspidor or cuspidor-holder, provided with a hinged cover removable bodily at will when lifted, a spring for automatically throwing said cover open, and a catch for locking the same in its closed position, substantially as described.

3. The body a of a cuspidor or cuspidor-

holder, provided with a hinged cover removable bodily at will when lifted, a spring for throwing said cover open, a suitable catch for locking the same in its closed position, and means for releasing said catch, substantially as described.

4. In a cuspidor or cuspidor-holder, the body a , provided with one or more overturned ears b^x , combined with the cover c , having one or more pintles b^2 , to engage the said overturned ears to form a detachable hinge, and mechanism for opening and closing the said cover, substantially as described.

In testimony whereof I have signed my name to this specification in the presence of two subscribing witnesses.

EDWARD F. DRAKE.
